FIG. A

UNITED STATES PATENT OFFICE

JULIUS BRODSKY, OF CHICAGO, ILLINOIS

SMOKE INDICATOR

Application filed April 18, 1927. Serial No. 184,610.

This invention relates to an improved smoke indicator, and has for one of its principal objects the provision of means which will afford to an engineer or fireman a visible showing, in the furnace room, of the density or blackness of the smoke issuing from any fuel burning plant.

One of the important objects of this invention is to provide a smoke indicator which can be placed in any convenient position with respect to the operator of the furnace or boiler to which it is connected, thereby affording a visible indication of the smoke density existing at any time in the stack or chimney.

Still another important object of this invention is to provide a smoke indicator which can be readily installed, and which is independent of obstructions in the boiler room and of the size and shape of the smoke passages, while at the same time allowing of ready adjustments, cleaning, or repairs.

Another important object of this invention is to provide a sample of smoke, a pure sample. It often is of importance to know what percentage of the flue gas is carbon monoxide, carbon dioxide, moisture, sulphur, etc.—a pure sample only will produce this information.

Another and still further important object of this invention is to provide an indicator for smoke, which is rugged and simple, composed of no moving parts, and which therefore is not subject to wear, and is always accurate, as it actually withdraws a small quantity of gas or smoke from the chimney or stack, placing the same in full view of the operator, thereby affording a positive indication of conditions in the chimney at all times.

Other and still further important objects of the invention will be apparent from the disclosures in the accompanying drawings and following specification.

The invention, in a preferred form, is illustrated in the drawings and hereinafter more fully described.

In the drawings:

Figure 1 is a front elevation of the improved smoke indicator of this invention, parts being shown in section.

Figure 2 is a vertical sectional view of the apparatus shown in Figure 1.

Figure 3 is a detail view illustrating a slight modification of the flow nozzle.

Figure 4 is a detail view illustrating another modification of the nozzle.

As shown in the drawings:

The reference numeral 10 indicates the body of the improved smoke indicator of the invention, comprising a casing which is approximately circular in form, being preferably conical and slightly elongated at its lower portion, as shown, and which may be formed of any suitable material, such as metal, or which, if desired, may be composed of glass. The casing 10 is provided with circular openings at its front and rear, into which are fitted panes of glass 12, which openings, of course, may be of any other shape, if desired. The transparent members 12 may be securely positioned by means of annular retaining rings 14 or by any other suitable means, and are supported in proper gaskets or the like 16, to provide a gas tight fit. Brackets 17 are provided to support the indicator casing on a wall or other support.

Leading into the top of the indicator body 10 is an intake pipe 18 which terminates in a nozzle 20 extending slightly into the center portion of the body 10. This lead-in pipe and nozzle is secured in position by means of a suitable packing gland or the like 22 which may be of any approved or suitable construction.

The shape of this nozzle 20 is important, and as indicated in Figure 1, tapers down from the full diameter of the pipe 18 to an orifice 24 substantially one quarter of the inner area of the pipe 18. The sides of this nozzle are formed gradually sloping, as indicated, and with gently rounded curves so as to provide a minimum of obstruction to the flow of the gases, while at the same time affording a nozzle which will direct a stream of gases across the diameter of the body 10 of a shape somewhat as indicated at 26 in Figure 1.

The fact that the diameter of the openings 24 is substantially smaller and preferably about one-half of the diameter of the

pipe 18 results in a natural increase in the velocity of the flow of the gas issuing from the orifice 24 which helps maintain the desired shape of the stream of smoke, preventing any filling of the interior of the casting, and further preventing clouding of the inner faces of the panes of glass 12. The smoke will be completely and cleanly withdrawn and will continue to issue in a steady stream as indicated so long as the device is in operation.

The apparatus can be easily taken apart for cleaning or repair, and, in fact, a simple reversal of the flow of air through the indicator 10 and the pipe 18 will suffice to blow out any accumulated soot or the like, which, of course, can be done at regular intervals for maintaining the apparatus at suitable operating efficiency. Steam may also be used for this purpose.

This stream of gases or smoke 26 is clearly visible on account of the transparent faces 12 of the body 10, and as the pipe 18 leads directly into the central or any other desired portion or part of a smoke stack or chimney, a representative sample of gases can be conveniently drawn therefrom, either continuously or at any stated time. Naturally, the pipe leading to the indicator is formed with as few bends as possible, and sharp bends are eliminated. The point at which the chimney, stack, or gas passage is tapped for indicating purposes is beyond the zone of complete combustion, as in this way a representative sample of smoke is obtained.

Inasmuch as the pressure in a chimney or stack is below atmospheric, it is necessary to create a still lower pressure at some point beyond the indicator 10 so as to provide a suitable flow of smoke or gases through the body 10 of the indicator. This is done by any suitable means, such as a steam jet 30 or the like which operates in conjunction with a Venturi tube 32, the same being affixed to the bottom of the body 10 of the indicator, or any other means for creating the necessary suction may be used, as a pump or fan. The gases drawn through the indicator may be disposed of in any suitable way, such as by means of a pipe or conduit.

The suction through the indicator must, of course, be such as to produce a relatively high velocity in the gases issuing from the nozzle 20, and various other shapes or designs of nozzles may be used, as for example that shown at 36 in Figure 3, where the transition from the entrance pipe into the body of the indicator is had by means of a rounded throat, as shown, this being formed in a tangential curve both to avoid the resistance caused by sharp corners and to preclude the possibility of the gases breaking away from the wall at high speeds, which, if it happened, would fill the indicator com-

pletely and render a correct determination very difficult.

As shown at 38 in Figure 4, a still further variety of flow nozzle may be used, which has a curved entrance leading tangentially into a very sharp cylindrical throat. The purpose of the curved entrance is to lead the gases or smoke smoothly to the orifice so that the same will issue in a straight cylindrical jet of the same diameter as the orifice.

It will be evident that herein is provided a smoke indicator which is readily available to the operator of furnaces, boilers, or the like, and which, besides effecting a considerable saving in fuel by indicating to the engineer the proper amount of air to be used with a furnace, will also be valuable for use in large cities where smoke ordinances are in effect. Instead of a single device for a stack, an indicator may be attached to each of a system of boilers so that the individual operation of each furnace may be accurately observed and controlled.

I am aware that many changes may be made and numerous details of construction varied throughout a wide range without departing from the principles of this invention, and I therefore do not purpose limiting the patent granted hereon otherwise than as necessitated by the prior art.

I claim as my invention:

1. A smoke indicator, comprising a casing, transparent sides in the casing, and means for passing a sample of smoke from a chimney through the casing, said means comprising a pipe leading from the chimney to the casing, and suction means for creating a pressure lower than that existing in the chimney at the far side of the casing, and a flow nozzle in the casing for controlling the appearance of the stream of gases taken from the chimney while passing through the casing.

2. A smoke indicator, comprising a casing, transparent sides in the casing, and means for passing a sample of smoke from a chimney through the casing, said means comprising a pipe leading to the chimney from the casing, and suction means for creating a pressure lower than that existing in the chimney at the far side of the casing, and a flow nozzle in the casing for controlling the appearance of the stream of gases taken from the chimney while passing through the casing, and at the same time increasing the velocity of said stream of gases.

In testimony whereof I affix my signature.

JULIUS BRODSKY.
